LUTHER L. KENNEDY, OF BROOKLYN, NEW YORK, ASSIGNOR TO MERGENTHALER LINOTYPE COMPANY, A CORPORATION OF NEW YORK.

LINE-CASTING MACHINE.

1,115,312.

Specification of Letters Patent. Patented Oct. 27, 1914.

Application filed November 7, 1910. Serial No. 591,076.

To all whom it may concern:

Be it known that I, LUTHER L. KENNEDY, a citizen of the United States, residing in the borough of Brooklyn, county of Kings, 5 and State of New York, have invented a new and useful Improvement in Line-Casting Machines, of which the following is a specification.

This invention has reference to line casting machines of the general organization represented in Letters Patent of the United States No. 436,532, wherein circulating matrices are assembled temporarily in line and presented between two confining jaws which 15 close the front of a slotted mold in order to form type characters on the edge of a type metal slug cast therein. In this class of machines it is frequently desirable to produce low, blank slugs; that is to say, slugs 20 without characters on the forward edge; and to this end the left hand jaw for confining the matrix line is adapted to be moved across, and to close, the face of the mold in the absence of matrices, so that the 25 slug will be cast in the mold against the rear surface of the jaw. Heretofore it has been necessary for the operator to use his hand to advance the jaw across the mold and hold it momentarily to the right. At 30 such time there is always liability of the molten metal escaping at the front of the mold, during the casting action, and burning the operator's hand. My invention is designed to overcome this danger. To this 35 end it consists in combining with the jaw adapted to close the mold a detent for holding it momentarily in position, the construction being such that this does not interfere with the ordinary automatic action of the 40 machine. With the exception of the parts herein described and claimed, the machine may be in all respects of the ordinary or of any suitable construction.

In the drawings, Figure 1 represents, in 45 perspective, a portion of the casting mechanism of a Mergenthaler linotype machine with my improvement applied thereto, portions being broken away to expose the other parts to view. Fig. 2 is a transverse section from right to left on the line 2--2, Figs. 1 and 3. Fig. 3 is a vertical cross section from front to rear on the line 3--3, Fig. 2. Fig. 4 is a view of one of the blank slugs above referred to.

Referring to the drawings, A represents 55 the vertical mold wheel or disk, B the slotted mold secured firmly in the wheel, and C the mouth of the melting pot, arranged to close against the back of the mold and deliver metal thereto under the influence of a plunger, not shown. D is a vertical jaw, commonly known as the right hand jaw, to confine the right end of the composed matrix line when the latter is in the casting position in front of the mold. 60 E is a second jaw, commonly known as the left hand jaw, adapted to confine the left end of the matrix line. The jaw E has a flat rear face, and is made of such size that it will cover and close the mold slot 65 throughout its length. It is formed with a supporting portion, e, arranged to slide horizontally in the main-frame K, so that the jaw may be moved endwise to and from the opposing jaw D, in order to confine the 70 matrix line, whatever its length, between the two jaws during the casting action. In the absence of matrices the jaw E may be advanced, as shown in Fig. 1, entirely across the mold and against the jaw D, so as to 75 cover the face of the mold during the casting of a blank slug. The right hand jaw D is permitted a slight movement endwise, and acts at its outer or rear end against a lever F, which controls a stop to prevent 80 the action of the plunger which delivers metal into the mold. The lever F is acted upon by a spring to hold the jaw D normally forward to the left, slightly beyond its operative position, the plunger being at 85 such time locked out of action. If the matrix line introduced between the two jaws is of the requisite length it crowds the jaw D backward, causing it to unlock the plunger and permit the casting action. All the 90 foregoing parts are constructed and operated in the ordinary manner.

When a blank slug is to be cast, the jaw E must be moved forward over the mold slot and against the jaw D, and the movement 100 continued until the jaw D actuates the stop lever F. It is the holding of the jaw E in this position which has heretofore been done by hand.

My invention consists in an automatic 105 detent to hold the jaw E momentarily in the extreme right hand position. In the form shown this consists in a vertical locking pin

G, mounted in the main frame K, and urged constantly downward by the spring g, its lower end being pointed and arranged to enter the notch or cavity H, in the sliding jaw E. When the jaw is moved forward the pin is thrust down into the cavity, and the jaws D and E are held to the right against the pressure of the spring actuated lever F. They will remain in this position during the casting action; after which the jaw E will be urged backward to the left, if the next slug be one with type characters thereon, as shown in Fig. 2, by the depending finger I, which is an ordinary part of the machine and is carried to the right and left. This finger I is the left hand or long finger of the ordinary carriage by which the composed line is transferred from the assembling elevator, through the intermediate channel, into the first elevator of the Mergenthaler linotype machine. This finger forms part of all commercial machines. As it is well understood by those skilled in the art, further description of its connection and operating devices is considered unnecessary herein. The pressure of this finger I is sufficient to overcome the resistance of the detent G and to carry the jaw E, as shown, to a position to admit the matrix line between the jaws. While I prefer to use the spring actuated pin as a detent because of its simplicity and cheapness, it is to be understood that it may be modified in form at will, or replaced by any other form of latch or detent which will hold the jaw E temporarily to the right, and which will permit the jaw to be forced backward to the left after the casting action.

Having described my invention, what I claim is:—

1. In a machine of the class described, the combination of a slotted mold, and the jaw E movable freely at will across the face of the mold to close the slot thereof, and the spring-actuated detent G to engage the jaw

when so moved and hold it yieldingly in 45 position.

2. In a machine of the class described, the combination of the mold, a sliding jaw E, adapted to cover the mold, a yielding detent to hold the jaw in said position, and means for automatically moving the jaw backward notwithstanding the resistance of the yielding detent.

3. In a machine of the class described, the combination of the movable jaw E and a yielding detent which engages and holds the jaw in adjusted position and is disengaged therefrom by the return movement of the jaw.

4. In a machine of the class described, and in combination with the sliding jaw E, a spring actuated detaining pin arranged to engage the jaw in one position and to be disengaged by the removal of the jaw therefrom.

5. In a machine of the class described, the combination of the pressure lever F, jaw D, the opposing jaw E, and a yielding detent adapted to hold the jaws E and D in their extreme right hand positions against the pressure of the lever F.

6. In a typographical machine, the combination of a slotted mold, a pump stop lever, a line clamping jaw movable freely at will across the face of the mold to close the slot thereof and adapted by such movement to shift the stop lever to inactive position, and a detent for holding the jaw in its moved position so as to maintain the stop lever in its inactive position.

In testimony whereof I hereunto set my hand this third day of November, 1910, in the presence of two attesting witnesses.

LUTHER L. KENNEDY.
